UNITED STATES PATENT OFFICE.

MELKER J. EICHHORN, OF CHICAGO, ILLINOIS, ASSIGNOR TO FREDERICK C. AUSTIN, OF SAME PLACE.

DESIGN FOR A CRUSHER-BED.

SPECIFICATION forming part of Design No. 26,545, dated January 19, 1897.

Application filed July 18, 1896. Serial No. 599,752. Term of patent 14 years.

To all whom it may concern:

Be it known that I, MELKER J. EICHHORN, a subject of the King of Sweden and Norway, residing at Chicago, in the county of Cook 5 and State of Illinois, have invented a certain new and original Design for Crusher-Beds, of which the following is a specification.

In the accompanying drawings, Figure 1 is a plan of a crusher frame or bed embodying 10 the essential features of my novel design. Fig. 2 is a vertical section taken longitudinally on line 2 2 in Fig. 1. Fig. 3 is a transverse section taken on line 3 3 in Fig. 1; and Fig. 4 is a longitudinal section of a portion 15 of the frame, as indicated by line 4 4 in Fig. 3.

The crusher-bed consists of an oblong structure having the sides $a a$ and ends a' and a'' . These sides and ends are formed by a flat horizontal oblong upper wall or top A and 20 substantially vertical interior and exterior side walls a^3 and a^2 , which extend around the interior and exterior edges of the top A, as shown in Figs. 2, 3, and 4. Along the lower edge of the inner side of the exterior side wall 25 a^2 of the sides $a a$ and end a' the horizontal flange A' (see Fig. 2) extends inwardly toward the inner wall a^3 . Through substantially the longitudinal middle of that portion of this flange A' which extends along the end a' a 30 hole or aperture is formed, (see Fig. 2,) and on each side of this hole a vertical web II extends between the upper surface of the flange A' and the lower portion of the inner face of the wall a^2 . Other webs are placed at suitable intervals across the space formed between the interior and exterior walls a^3 and a^2 , as shown by the dotted lines in Fig. 1. The outer face B of that portion of the interior wall a^3 which extends across the end a' 35 is inclined from the vertical toward the interior of the crusher-bed, as shown in Fig. 2, and extending from end to end of its upper and lower edges are the projecting or overhanging lips b. The opposing surfaces of 40 these lips b are inclined to the face B so as to form a slightly acute angle therewith, and their extreme upper and lower surfaces are desirably curved or rounded.

Projecting outwardly and transversely to

the length of the bed at each side thereof, near 50 its left-hand end, are the lugs C. These lugs C are attached to the exterior wall a^3 of the sides $a a$ at corresponding points, which are desirably situated below the lower edges of said walls (see Figs. 2 and 4) and taper toward 55 their outer ends, as shown in Fig. 1. A central aperture or hole extends longitudinally through each of these lugs C, as shown in Figs. 2 and 4. Between the interior and exterior walls a^3 and a^2 of each side a and to 60 the right of the face B an intermediate wall or partition E, Fig. 3, extends longitudinally of said sides between two of the previously-mentioned webs or partitions D and D'. One of these webs or partitions, D, is substantially 65 vertical and the other one, D', is inclined downwardly and to the right. Both of them extend inwardly from the exterior wall a^2 , their upper portions to the interior wall a^3 and their lower portions only to the intermediate 70 walls E, and both are attached at their lower ends to the flange A', which latter, however, does not extend between such end portions of the webs D D'.

The upper portions of the intermediate 75 walls E are connected with the inner wall a^3 of the bed by the solid portions F, Figs. 3 and 4, which latter are provided with horizontal holes or apertures extending therethrough transversely to the length of the bed, as shown 80 in Fig. 4.

Near the right-hand end of the bed the upper surface of the top A of each side a is correspondingly elevated, and these elevated portions are transversely hollowed or concaved, as at G, the hollow or concave surfaces thus formed being in alinement with one another. Below these elevated portions 85 portions of the interior wall a^3 are cut away, so as to form arched recesses a^5 , as shown in 90 Fig. 2.

What I claim is—

The design for a crusher-bed, substantially as herein shown and described.

MELKER J. EICHHORN.

Witnesses:

ARTHUR F. DURAND,
RETA M. WAGNER.
